RELEASING ROPE SOCKET

Cecil H. Sweet, Brea, Calif., assignor of one-half
to Weldon C. Erwin, Brea, Calif.

Application August 27, 1934, Serial No. 741,714

6 Claims. (Cl. 255—26)

This invention relates to a connection for well drilling equipment and relates more particularly to a rope socket. A general object of this invention is to provide an effective, dependable 5 rope socket that may be readily released.

Various tools employed in well drilling operations are operated on wire rope lines or cables. Devices known as rope sockets are usually employed to connect the tools with the lower ends of 10 the cables. The typical rope sockets now in general use are not capable of being released in the well. Cable operated tools frequently become caught in the wells and as the usual rope sockets cannot be released the cables must be cut to free 15 them from the caught tools. When a tool becomes caught in a well it is customary to pull upwardly on the cable in an attempt to dislodge or free the tool. The cable sometimes breaks during such attempts to recover a caught tool. 20 It is extremely difficult, if not impossible, to cut a cable immediately adjacent a tool caught in a well and a portion of the cable usually remains on the caught tool following the cutting and withdrawal of the cable. Likewise when a cable 25 breaks during an attempt to dislodge a caught tool it usually breaks some distance above the tool. The portion of the broken or cut cable remaining on the tool prevents the proper engagement of the fishing tools with it and thus greatly 30 hampers the fishing operations. In many instances prolonged expensive fishing operations are necessary to recover a caught tool because of the presence of a portion of cable on the tool.

Another object of this invention is to provide 35 a rope socket for connecting a wire rope or cable with a well tool that may be easily and quickly released to free the cable from the tool. When a well tool, connected with a wire rope line or cable by the rope socket of the present invention, becomes caught in a well, the socket may 40 be readily released so that the entire cable may be withdrawn from the well leaving the caught tool and the body of the socket freely accessible and engageable by fishing tools.

Another object of the invention is to provide 45 a releasing rope socket of the character mentioned that normally dependably connects the line or cable with the well tool and cannot accidentally release during operation of the tool.

Another object of the invention is to provide 50 a rope socket of the character mentioned that may be released when desired or necessary by a weight element dropped or run into the well on the cable. The socket of the present invention is released by a weight which is adapted to function

under conditions in which a device for striking a blow might become caught or made inoperative.

Another object of the invention is to provide a 5 rope socket of the character mentioned that embodies a tubular body to be connected to the well tool, which body has its upper end exposed and open after the releasing of the socket and the withdrawal of the cable so that a spear or similar internal fishing tool may be run into its upper 10 end to grip its interior or a socket, overshot, or other external fishing tool may be run down over the body to grip its exterior for the purpose of recovering the caught tool.

Another object of the invention is to provide 15 a releasing rope socket that may be designed to allow relative rotation between the wire rope line or cable and the well tool.

Another object of the invention is to provide 20 a releasing rope socket that will not become sanded up or made inoperative by accumulations of sand or the like.

A further object of the invention is to provide 25 a releasing rope socket that is simple and inexpensive and that is adapted for use in connection with well tools of various characters.

The various objects and features of my invention may be fully understood from the following detailed description of a typical form and application of the invention, throughout which 30 description reference is made to the accompanying drawings, in which:

Fig. 1 is a side elevation of the rope socket of this invention connecting a line with a tool and illustrating the weight element on the cable 35 above the socket. Fig. 2 is an enlarged longitudinal detailed sectional view of the releasing rope socket illustrating the parts in the normal positions where the socket connects the line or cable with the tool. Fig. 3 is an enlarged 40 fragmentary longitudinal sectional view of the principal parts of the socket in the normal positions. Fig. 4 is a view similar to Fig. 3 showing the dogs or latches released and the stem moved to its down or released position by the weight 45 element. Figs. 5 and 6 are enlarged transverse detailed sectional views taken as indicated by lines 5—5 and 6—6, respectively, on Fig. 1 and Figs. 7 and 8 are enlarged, transverse detailed 50 sectional views taken as indicated by lines 7—7 and 8—8, respectively, on Fig. 2.

The releasing rope socket of the present invention includes, generally, a body 10 adapted to be attached to a well tool T, a stem or mandrel 11 to be connected to a line L and normally 55

extending into the body 10, a releasable connection 12 between the mandrel 11 and body 10, a control 13 normally holding the connection 12 against releasing and a weight element 14 adapted to actuate the control 13 whereby the connection 12 may be released.

The body 10 is a socketed or tubular member having a central longitudinal opening 15. The body 10 is intended to be connected with the upper end of a well tool and its opening 15 normally receives the mandrel 11. In the drawings I have illustrated a suitable connecting member 16 threaded on the lower end of the body 10 for the purpose of connecting the body with the tool T. The connecting member 16 has a socket 17 in its lower end receiving a threaded pin 18 of the tool T. The body opening 15 has a cylindrical enlargement 19 in its upper portion terminating in an upwardly facing shoulder 20. A restriction or annular flange 21 is provided on the wall of the body opening 15 at a point between the opposite ends of the body. The lower end of the flange 21 constitutes a downwardly facing shoulder 22 on the interior of the body 10. If desired ports 23 may be provided in the connecting member 16 to put the body opening 15 in communication with the well bore.

The body 10 is preferably provided with means whereby it may be readily engaged and held by a socket, overshot or similar type of fishing tool as well as by a spear or other internal fishing tool. A series of spaced annular grooves is provided in the exterior of the body 10 at a suitable distance below its upper end to provide a plurality of downwardly facing wickers or shoulders 24. The shoulders 24 are adapted to be engaged by the slips of an overshot, socket or the like. A series of annular downwardly facing wickers or shoulders 25 is provided on the wall of the body opening 15 below the shoulder 20 for engagement by the slips or gripping parts of a spear or similar fishing tool.

The mandrel 11 is intended to be suitably rigidly connected to the line L of wire rope or cable. The mandrel 11 is shiftably or freely received in the body opening 15 and projects from the upper end of the body 10. In the particular application of the invention illustrated in the drawings a typical or common rope socket 26 is secured to the lower end of the line L and a pin 27 on the upper end of the mandrel 11 is threaded into the socket 26 to connect the mandrel with the line L. Wickers or shoulders 26a may be provided on the socket 26 to facilitate its engagement by a fishing tool in the event that the line L breaks during the operation of the well tool T. A central longitudinal opening 28 is provided in the mandrel 11 for the purpose to be subsequently described. An outwardly projecting flange 29 is provided on the mandrel 11 within the enlargement 19 of the body opening and is adapted to cooperate with the shoulder 20 to limit the inward or downward movement of the mandrel.

The connection 12 normally holds the mandrel 11 against disconnection from the body 10 and is releasable by a strain on the line L. The releasable connection 12 includes a plurality of flexible fingers 30 on the lower end of the mandrel 11. The fingers 30 may be integral with the mandrel 11 and may be formed by cutting a plurality of spaced longitudinal slots in the lower portion of the mandrel. The fingers 30 extend downwardly through the flange 21 and are provided adjacent their lower ends with outwardly project-

ing enlargements or lugs 31. The upper sides 32 of the lugs 31 oppose the shoulder 22 and cooperate therewith through the medium of an anti-friction bearing 33 to hold the mandrel against upward displacement or detachment from the body 10. The fingers 30 may normally tend to spring outwardly so that the lugs 31 cooperate with the bearing 33. The fingers 30 are sufficiently flexible to bend inwardly when an upward strain is put on the mandrel 11 to cause slippage between the upper surfaces 32 of the lugs 31 and the lower side of the bearing 33. The upper faces 32 of the lugs 31 and the lower side of the anti-friction bearing 33 are preferably inclined upwardly and inwardly so that the faces 32 may freely slip or slide on the bearing and cause inward flexing of the fingers 30 when the mandrel is moved upwardly relative to the body 10. The anti-friction bearing 33 interposed between the lugs 31 and the shoulder 22 allows substantially free relative rotation between the body 10 and mandrel 11.

Means may be provided for absorbing shocks to the mandrel 11 and for urging the mandrel upwardly so that the lugs 31 normally cooperate with or bear against the bearing 33. A spring 34 surrounds the mandrel 11 within the body opening 15 and is arranged under compression between opposing shoulders 35 to yieldingly hold the body 10 and mandrel 11 in positions where the lugs 31 cooperate with the bearing 33. The spring 34 yields under but resists inward movement of the mandrel 11 with respect to the body 10 and thus acts to absorb shocks. A set screw 36 may be provided to attach the spring 34 to the mandrel 11 so that the spring is withdrawn from the body 10 when the mandrel is released from the body 10 and removed from the well on the line L.

The control 13 normally holds the fingers 30 against inward movement and disengagement from the bearing 33 and thus normally prevents disconnection of the mandrel 11 from the body 10. The control 13 is adapted to be released or actuated by the weight element 14 to allow the inward flexing of the fingers 30 when the mandrel 11 is moved upwardly with respect to the body 10 to release the device or socket. In accordance with the preferred form of the invention the control 13 includes a longitudinally shiftable stem 37 in the opening 28 of the mandrel 11. The stem 37 extends downwardly between the fingers 30 and has an enlargement or head 38 within the lower portions of the fingers. When the stem 37 is in the position illustrated in 2 and 3 of the drawings the head 38 positively prevents inward flexing of the fingers 30 and disengagement of the lugs 31 from the bearing 33. The upper end of the head 38 is preferably inclined upwardly and inwardly to allow the fingers 30 to gradually flex inwardly when the mandrel is moved upwardly following the release of the control 13.

The control 13 includes a sleeve 39 surrounding the mandrel 11 and extending downwardly into the enlargement 19 of the body opening. The sleeve 39 projects a suitable distance upwardly from the upper end of the body 10 and is shiftable on the body. An enlargement or head 41 is provided on the upper end portion of the stem 37 and slidably or shiftably fits the opening 28. A connection is provided between the stem 37 and the sleeve 39. This connection may include a pin 40 arranged in a transverse opening in the head 41 and extending through longitudinal 75

slots 42 in the wall of the mandrel 11. The opposite end portions of the pin 40 are received in openings 43 in the sleeve 39. A screw 44 holds the pin 40 against displacement. The weight element 14 is adapted to engage and rest on the sleeve 39 to move the stem 37 downwardly to a position where its head 38 is below the fingers 30 so that the fingers may be flexed inwardly when the mandrel 11 is moved upwardly by applying a strain to the line L.

Latch means is embodied in the control 13 to normally hold the stem 37 against downward movement. The latch means is releasable by the weight element 14 and includes one or more dogs 45 carried by the mandrel 11 for cooperating with the sleeve 39. In the drawings I have shown two like dogs 45 pivotally supported in longitudinal slots 46 in the mandrel 11. The dogs 45 have outwardly projecting fingers 47 adjacent their lower ends and the lower portions of the dogs are normally received in the upper end of the sleeve 39. The fingers 47 of the dogs cooperate with a groove 48 in the interior of the sleeve 39. A spring 49 is arranged under compression between the pivoted dogs 45 to normally yieldingly hold the dogs in their out or active positions where the fingers 47 cooperate with the groove 48. The dogs 45 are each provided with cam like parts projecting from the slots 46 and presenting downwardly and outwardly inclined surfaces 50. The surfaces 50 are engaged by the weight element 14 to cause inward movement of the dogs and disengagement of the fingers 47 from the sleeve 39 as will be subsequently described. A spiralled spring 51 may be arranged under compression between the lower end of the head 38 and the connecting member 16 to yieldingly urge the stem 37 upwardly and relieve the fingers 47 of strain and shock. A screw 52 connects the spring 41 with the stem 37 so that the spring is removed from the body 10 together with the mandrel when the device or socket is disconnected.

The weight element 14 is adapted to be passed or run into the well to depress the sleeve 39 when it becomes desirable or necessary to release the line L from the tool T. In accordance with the invention the weight element 14 is constructed so that it may be readily arranged or assembled around the line L at the well derrick and allowed to slide or pass downwardly on the line to come to rest on the sleeve 39. The weight element 14 includes a tubular body 54 provided with a longitudinal slot 55. The slot 55 extends from one end to the other of the body 54 and is adapted to pass or admit the line L whereby the body may be arranged on the line. The body 54 is preferably of substantial length to be of sufficient weight to properly release the dogs 45 and depress the sleeve 39 and stem 37.

Means is provided for preventing disengagement of the weight element 14 from the cable L. Split collars are provided on the opposite ends of the body 54. One section 56 of each collar is welded or otherwise attached to the body 54. The other section 57 of each collar is adapted to be passed into the end portion of the body 54 to a position where it abuts the section 56 and closes or extends across the slot 55. The sections 57 are arranged in place after the body 54 has been passed onto the line L. Screws 58 may be employed to attach the removable collar sections 57 to the body 54. Spaced tangential openings 59 may be provided in the body 54 to intersect the slot 55. Pins 60 may be arranged in the

openings 59 to pass transversely through the slot 55. The ends of the pins 60 may be peaned over to prevent the accidental displacement of the pins. The pins 60 prevent the line L from bending or looping outward through the slot 55 when the weight element 14 is passing downwardly on the line.

The releasing rope socket of the present invention is adapted to be assembled as illustrated in Figs. 1, 2 and 3 of the drawings to connect the well tool T with the lower end of the line L. The tool T is adapted to be run into and out of the well and operated as may be required. The releasing rope socket normally forms a strong dependable connection between the line L and the tool T.

In the event that the tool T becomes stuck or caught in the well and cannot be dislodged by putting safe upstrains on the line L it may become necessary to release the line L from the tool T. The body 54 of the weight element 14 may be easily arranged on the line L and secured against displacement therefrom by the collar sections 57. The pins 60 may be inserted in the openings 59 to prevent looping or buckling of the line L through the slot 55. When the weight element 14 is properly assembled on the line L at the well derrick it may be dropped to slide or pass downwardly on the line. The weight element 14 passes downwardly on the line L and passes over the rope socket 26. The lower collar sections 56 and 57 move into engagement with the inclined surfaces 50 of the dogs 45 and the weight element 14 operates to move the dogs inwardly. The inward movement of the dogs 55 releases their fingers 47 from the groove 48 and when the weight element 14 comes to rest on the sleeve 39 its weight moves the sleeve downwardly. After this downward movement of the sleeve 39 the weight element 14 comes to rest on the upper end of the body 10. The downward movement of the sleeve 39 causes corresponding downward movement of the stem 37 which moves the head 38 downwardly from between the fingers 30. Following the actuation or the release of the control 13 by the weight element 14 a suitable pull or upstrain is put on the line L to release the connection 12 and withdraw the mandrel 11 from the body 10. The upstrain on the line L causes the surfaces 32 of the lugs 31 to slide on the inclined end of the bearing 33 and results in inward flexing of the fingers 30. In this manner the fingers 30 are disengaged from the bearing 33. After the disengagement of the lugs 31 from the bearing 33 the mandrel 11 is free to be moved upwardly out of the body 10. The springs 34 and 51 are connected to the mandrel 11 so that they are withdrawn from the body 10 together with the mandrel. The sleeve 39 and the weight element 14 are supported by the flange 29 to be withdrawn from the well on the line L.

The entire line L, together with the mandrel 11, the parts connected with the mandrel and the weight element 14 may be readily withdrawn from the well following the release of the connection 12 as described above. The withdrawal of the line L from the well leaves the body 10 of the device open and accessible for ready engagement by fishing tools. The upper end of the body 10 is open and entirely exposed so that a spear or similar fishing tool may be run into it to engage the shoulders 25. If desired or found more practical a socket or overshot may be run downwardly over the upper end of the body 10 to bring its gripping parts into engagement with

- the shoulders 24. The fishing tool in directly cooperating with the wickers or shoulders of the body 10 in most cases may readily dislodge the tool T and recover it from the well. It is to be particularly noted that the socket body 10 is open and freely accessible following the withdrawal of the mandrel 11 so that the fishing operations are not hampered by the presence of a cable or any other part.
- Having described only a typical preferred form and application of my invention, I do not wish to be limited or restricted to the specific form and application herein set forth, but wish to reserve to myself any modifications or variations that may appear to those skilled in the art or fall within the scope of the following claims:
- Having described my invention, I claim:
1. A device for connecting a well tool with an operating cable including a mandrel on the cable, a body connected with the tool having an opening for receiving the mandrel, a part on the mandrel releasably cooperating with the body to connect the mandrel therewith, a member movable in the mandrel and normally holding the part against release from the body, a sleeve at the exterior of the mandrel connected with the member, and an element adapted to be run into the well to cooperate with the sleeve and move the member to an inoperative position.
  2. A device for connecting a well tool with an operating cable including a mandrel on the cable, a body connected with the tool having an opening for receiving the mandrel, a part on the mandrel releasably cooperating with the body to connect the mandrel therewith, a stem movable in the mandrel and normally holding the part against release from the body, a sleeve at the exterior of the mandrel connected with the stem, a latch cooperating with the sleeve to hold the stem against movement, and an element to be run into the well to release the latch and move the stem to an inoperative position.
  3. A device for connecting a well tool with an operating cable including a mandrel on the cable, a body connected with the tool having an opening for receiving the mandrel, a flexible finger on

the mandrel having releasable cooperation with the body to connect the mandrel therewith, a movable member normally holding the finger against release from the body, and means for moving the member out of retaining cooperation with the finger.

4. A device for connecting a well tool with an operating cable including a mandrel on the cable, a body connected with the tool having an opening for receiving the mandrel, a shoulder on the body, flexible fingers on the mandrel cooperating with the shoulder to connect the mandrel and body, a movable member normally holding the fingers against disengagement from the shoulder, latch means holding the member against movement and gravity means for releasing the latch means and moving the member to a position where the fingers may disengage from the shoulder.

5. A device for connecting a well tool with an operating cable including a mandrel on the cable, a body connected with the tool having an opening for receiving the mandrel, a shoulder on the body, flexible fingers on the mandrel and body, an anti-friction bearing between the fingers and shoulder, a movable member normally holding the fingers against disengagement from the shoulder, latch means holding the member against movement and gravity means for releasing the latch means and moving the member to a position where the fingers may disengage from the shoulder.

6. A device for connecting a well tool with an operating cable including a mandrel on the cable, a body connected with the tool having an opening for receiving the mandrel, a part on the mandrel releasably cooperating with the body to connect the mandrel therewith, a stem movable in the mandrel and normally holding the part against release from the body, a sleeve at the exterior of the mandrel connected with the stem, a latch cooperating with the sleeve to hold the stem against movement, and a weight to be passed down on the cable to release the latch and move the stem to an inoperative position.

CECIL H. SWEET.
